(57) **CLAIM**

The ornamental design for a lure cover, as shown and described.

DESCRIPTION

FIG. 1 is a top, front, right-side perspective view of a lure cover.

FIG. 2 is a front elevation view shown at an enlarged scale of the lure cover, with the rear elevation view being a mirror image.

FIG. 3 is a right-side elevation view of the lure cover, with the left-side elevation view being a mirror image.

FIG. 4 is a top plan view of the lure cover.

FIG. 5 is a bottom plan view of the lure cover; and, FIG. 6 is a top, front, right-side perspective view shown with an indeterminate length.

1 Claim, 2 Drawing Sheets
